FLUID PRESSURE DISPENSING APPARATUS

Charles A. Corcoran, New York, N. Y.

Application July 15, 1933, Serial No. 680,605

6 Claims. (Cl. 225—18)

The present invention relates to fluid pressure dispensing devices or apparatus and has particular relation to devices for supplying gas under pressure to the interior of a receptacle for expelling a beverage or other fluid substance contained therein.

One of the objects of the present invention is to provide a device of the character described which is entirely self contained and which is 10 adapted to be inserted as a unit and sealed within a beer barrel or the like and which is adjustable to supply gas continuously at a predetermined constant pressure, and at desired intervals until exhausted, to the interior of the barrel 15 in order to expel the beer at the desired pressure.

Another object of the invention is to provide a device of the character described in which the pressure adjusting means is inaccessible after the device has been sealed within the receptacle so 20 that it cannot be tampered with or its adjustment altered without first unsealing the receptacle and removing the device bodily therefrom.

Still another object of the invention is to provide a device of the character described which is 25 adapted to be initially charged with a suitable gas under pressure or in which the pressure chamber may be charged with carbon dioxide in solid form, such as dry ice, the transformation of which into carbon dioxide gas will furnish the desired 30 pressure.

With such objects in view, as well as other advantages which may be incident to the use of the improvements, the invention consists in the use of the parts and combinations thereof hereinafter 35 set forth and claimed, with the understanding that the several necessary elements constituting the same may be varied in proportions and arrangement without departing from the nature and scope of the invention.

40 In order to make the invention more clearly understood there are shown in the accompanying drawing means for carrying the same into practical effect, without limiting the improvements, in their useful applications, to the particular constructions which, for the purpose of explanation, have been made the subject of illustration.

In the said drawing:—

Figure 1 is a fragmentary vertical sectional view illustrating the improved pressure dispensing device as being detachably secured to the bung of a beer container, and

Figure 2 is an enlarged vertical sectional view of the pressure dispensing device shown in Figure 1.

Referring to the drawing, the device is shown as comprising a cylindrical casing 1 having heads 2 and 3 threaded into the upper and lower ends thereof respectively and which is provided with a transverse wall or partition 4 intermediate its ends which divides the interior of the casing into a lower chamber 5 and an upper chamber 6. The lower chamber 5 constitutes the pressure chamber and may be charged with gas under pressure or supplied with solidified carbon dioxide while the upper chamber 6 constitutes a pressure equalizing chamber and houses the reducing valve mechanism presently to be described. A ball or other check valve 7 is threaded into the lower head 3 and is provided with a 70 depending nipple 8 adapted to be engaged by suitable pressure hose when the chamber 5 is initially charged with gas under pressure. This initial charge of gas under pressure is considerably in excess of that required to expel the entire 75 contents of the receptacle or barrel in which the device may be installed or assembled, thereby obviating the necessity of replacing the pressure device before the receptacle is emptied. In the event that it is desired to charge the chamber 5 80 with solidified carbon dioxide, the lower head 3 is unscrewed by a wrench or other tool applied to a squared boss 9 cast integrally with the head 3.

Communication between the pressure chamber 5 and the valve chamber 6 is established through 85 the medium of a duct 10 of relatively small cross-sectional dimensions and the flow of gas through said duct is controlled by a valve 11 carried by one end of a vertically swinging arm 12 for engagement with a valve seat 13, preferably of relatively soft metal. The other end of the arm 12 is pivotally mounted upon a pin 14 carried by vertically extending ears 15 cast integrally with the partition 4. The outer end of the arm 12 is urged downwardly so as to seat the valve 11 in 90 order to interrupt the flow of gas through the duct 10, by means of a lever 16 which is pivotally mounted, as at 17, between a pair of ears 18 which may also be cast integrally with the partition 4. One end of the lever 16 is provided with 95 a cam surface 19 for engagement with the outer end of the arm 12 and the other end of said lever is pivotally mounted, as at 20, to the lower end of a vertically extending stud 21. This stud extends axially through a flexible diaphragm 22 100 preferably consisting of a relatively thin sheet of phosphor bronze and is secured thereto by means of a conical nut 23. The diaphragm 22 is clamped between an annular flange 24 cast integrally with the walls of the casing 1 and a ring 25 which is 105

110

inserted through the upper end of the casing with a tight pressed fit.

The diaphragm 22 is urged downwardly by the means of a coil spring 26 the lower end of which 5 seats upon the conical nut 23 and the upper end of which engages a flanged plate 27 secured to the lower end of an adjusting screw 28. This screw is threaded into the upper head 2 and is provided with a slot 29 by means of which it may 10 be turned by a screw driver or similar tool in order to adjust the tension exerted by the spring 26 against the diaphragm 22. The adjusting screw 28 is maintained in adjusted position by means of a lock nut 30 which is threaded onto 15 the upper end of the screw for clamping engagement with the upper surface of the head 2.

Communication between the valve chamber 6 and the interior of the receptacle in which the device is sealed is established through a port 31 20 also of relatively small cross-sectional dimension. A check valve may be provided if desired for preventing the contents of the receptacle from entering the chamber 6 through the part 31.

The upper end of the casing 1 is exteriorly 25 screw threaded, as indicated at 32, to enable the device to be threaded into an internally threaded bung or closure 33 of a beverage receptacle 34, as indicated in Figure 1. If desired, the device may be detachable and secured to the bung 33 by 30 means of a suitable bayonet joint connection (not shown).

Assuming that the pressure chamber 5 is charged with a suitable gas under pressure and that the device is mounted within the receptacle 35 35 as illustrated in Figure 1, gas will escape from the chamber 5 through the duct 10 into the valve chamber 6 and thence through the duct 31 into the receptacle 34. When the pressure of the gas within the receptacle 34 and valve chamber 6 reaches a value determined in advance by the 40 proper adjustment of the tension of the spring 26, the diaphragm 22 will be flexed upwardly against the action of the spring 26. This movement of the diaphragm 22 elevates the stud 21 and the lever arm 16 secured thereto and causes the cam portion 19 to swing downwardly and depress the arm 12 so as to seat the valve 11 and interrupt the escape of gas from the pressure chamber 5.

The pressure desired within the receptacle varies in accordance with the substance being dispensed. In the event that the contents of the receptacle is a beverage the pressure within the receptacle may be selectively regulated to meet the predetermined discharge demands by the 55 proper adjustment of the screw 28 above described. For example such pressure, when the contents to be dispensed consists of beer, may be substantially 20 pounds to the square inch. This pressure, being in excess of atmospheric 60 pressure, excludes air from the outer atmosphere from the receptacle the presence of which would impair the flavor and quality of the beer when the device is employed to dispense beer.

As shown in Figure 1 the beverage may be dispensed through a suitable faucet 35 which communicates with a vertically extending tube 36 the lower end of which terminates adjacent to the bottom of the receptacle and is provided with a 70 strainer 37.

When the faucet 35 is opened the pressure of the gas within the receptacle 34 will expel the beverage until the pressure within the receptacle and valve chamber 6 decreases to a value which 75 is insufficient to maintain the valve 11 closed.

When this period is reached the spring 26 will flex the diaphragm 22 downwardly so as to permit the valve 13 to open under the pressure of the gas within the pressure chamber 5. As soon as the pressure of the gas thus supplied to the receptacle again reaches the predetermined desired value the diaphragm 22 will again be flexed upwardly and close the valve 11 as hereinbefore described.

It will be apparent from an inspection of the drawing that when the device is assembled as shown in Figure 1, the adjusting screw 28 is housed within the bung 33 and cannot be tampered with or its adjustment altered without first unscrewing the bung and removing the device from the receptacle and then detaching the device from the bung so as to expose the adjusting screw 28. This insures that under ordinary conditions the device is fool proof and effectively prevents an explosion from occurring should the screw 28 be manipulated so as to permit an excessive gas pressure to be built up within the receptacle when the receptacle is sealed.

It is not intended to limit the invention to the particular constructions shown in Figure 1, as other means may be provided for mounting the device within the receptacle 34. For example, the device may be detachably secured to a well of the receptacle or to a float and might even be in the form of a cartridge movable freely within the receptacle.

The type or nature of gas employed preferably corresponds to that liberated by the fluid being dispensed. For example, when the receptacle is employed for beer the pressure chamber 5 should 110 be charged with carbonic acid gas, which is odorless and tasteless. Compressed air may be utilized for the same purposes, such as in the dispensing of oil or grease or other materials which will not deteriorate by contact with air.

Also, the device may be provided with a suitable gauge to indicate accurately the pressure at which the reducing valve is adjusted to operate. A suitable safety valve may be provided in the faucet or elsewhere to insure against an excessive pressure from developing within the receptacle should the reducing valve be adjusted improperly.

What is claimed is:

1. A device of the character described comprising a casing adapted to be sealed within a receptacle containing a material to be dispensed, said casing having a pressure chamber for containing a charge of gas under relatively high pressure adapted to be supplied to said receptacle to expel the material therefrom; means responsive to the pressure of gas within said receptacle for releasing gas from said pressure chamber into said receptacle when the gas pressure in said receptacle decreases to a predetermined value and for interrupting the flow of gas from said chamber when the pressure in said receptacle increases to a predetermined value; and means carried by said casing and inaccessible from without said receptacle when said casing is sealed within said receptacle, for adjusting said pressure responsive means to operate at a selected pressure within said receptacle, whereby the material is expelled from said receptacle at a predetermined constant pressure.

2. A device of the character described comprising a casing adapted to be sealed within a receptacle containing a material to be dispensed, said casing having a pressure chamber for containing a charge of gas under relatively high pressure adapted to be supplied to said receptacle to expel

the material therefrom; a reducing valve responsive to the pressure of gas within said receptacle for releasing gas from said pressure chamber into said receptacle when the gas pressure in said 5 receptacle decreases to a predetermined value and for interrupting the flow of gas from said chamber when the pressure in said receptacle increases to a predetermined value; and means carried by said casing and inaccessible from without 10 said receptacle when said casing is sealed within said receptacle, for adjusting said reducing valve to operate at a selected pressure within said receptacle, whereby the material is expelled from said receptacle at a predetermined constant pressure. 15

3. A fluid pressure dispensing device comprising a receptacle for containing a liquid to be dispensed and having an opening therein, a closure for said opening and having a socket provided 20 on its inner face inaccessible from without said receptacle when said closure is in an operative position with respect to said opening, a casing removably secured within said socket, said casing including a pressure chamber for containing 25 a supply of gas under pressure and means responsive to the pressure within said receptacle for controlling the flow of gas from said pressure chamber to the interior of said receptacle, and adjusting means carried by said casing and disposed within said socket for regulating said pressure responsive means to operate at a selected 30 pressure.

4. A fluid pressure dispensing device comprising a receptacle containing a liquid to be dispensed and having an opening therein, a closure for said opening and having a socket provided 35 on its inner face inaccessible from without said receptacle when said closure is in an operative position with respect to said opening, a casing removably secured within said socket, said casing including a pressure chamber for containing 40 a supply of gas under pressure and a reducing valve for controlling the flow of gas from said pressure chamber to the interior of said receptacle, and adjusting means carried by said cas- 45

ing and disposed within said socket for regulating said reducing valve to operate at a selected pressure.

5. A fluid pressure dispensing device comprising a receptacle for containing a liquid to be dispensed and having an opening therein, a closure for said opening and having a socket on its inner face inaccessible from without said receptacle when said closure is in an operative position with respect to said opening, a casing removably secured within said socket and adapted to be sealed within said receptacle, said casing having a pressure chamber for containing a charge of gas under relatively high pressure adapted to be supplied to said receptacle to expel the material therefrom, and a chamber containing a reducing valve responsive to the pressure of gas within said receptacle for releasing gas from said pressure chamber into said receptacle when the gas pressure in said receptacle decreases to a predetermined value and for interrupting the flow of gas from said chamber when the pressure in said receptacle increases to a predetermined value; and means carried by said casing and housed within said socket for adjusting said reducing valve to operate at a selected pressure within said receptacle, whereby the material is expelled from said receptacle at a predetermined constant pressure. 90

6. A fluid pressure dispensing assembly comprising a receptacle adapted to contain a liquid to be dispensed, a gas pressure storage device adapted to be inserted in said receptacle as an entirety and sealed therein, said device comprising a casing including a pressure chamber for containing a supply of gas under pressure and a reducing valve arranged to control communication with said chamber and the flow of gas therefrom to the interior of said receptacle, and adjusting means carried by said device and inaccessible from without said receptacle when said device is sealed within said receptacle for regulating said reducing valve to operate at a selected pressure. 105
